UNITED STATES PATENT OFFICE.

JOSEPH W. KOVACH AND TONI MARKOVICH, OF AURORA, MINNESOTA.

LOCK AND KEY.

1,426,573.

Specification of Letters Patent. Patented Aug. 22, 1922.

Application filed December 17, 1920. Serial No. 431,361.

To all whom it may concern:

Be it known that we, JOSEPH W. KOVACH and TONI MARKOVICH, respectively a citizen of the United States and subject of the 5 King of Austria, both residing at Aurora, in the county of St. Louis and State of Minnesota, have invented certain new and useful Improvements in Locks and Keys, of which the following is a specification, reference 10 being had therein to the accompanying drawing.

This invention relates to a lock and key therefore and has particular reference to a mortise lock such as used in connection with 15 a chest, drawer, trunk and the like, where the lock is manipulated from one side only.

The principal object of the invention is to provide a lock of this character in which the bolt remains in its locked position until the 20 key is again inserted within the lock for releasing the bolt retaining mechanism, thus preventing any possibility of the bolt being released from the locked position by an instrument directly engaging said bolt.

Another object is to provide a key for 25 such a lock having an auxiliary key associated therewith for releasing the bolt retaining device prior to the withdrawal of the bolt by the key proper.

Other objects and advantages of the 30 peculiar construction of the invention will appear in the further description thereof.

In the accompanying drawings forming 35 part of this application and in which like reference characters indicate like parts:

Figure 1 is a front elevation of the completely assembled lock;

Figure 2 is a similar elevation of the inside of the lock after the covering plate is 40 removed;

Figure 3 is a similar elevation of the opposite side of the intermediate plate to that shown in Figure 2, and in locked position;

Figure 4 is a similar view to Figure 3 45 showing the bolt in unlocked position;

Figure 5 is an enlarged front edge elevation of Figure 2;

Figure 6 is an enlarged vertical sectional view on the line 6—6, Figure 4;

Figure 7 is an end elevation of the novel 50 form of key for manipulating the lock; and

Figure 8 is a side elevation of the key.

The supporting members of the lock comprise the base plate 1, the covering plate 2 55 and the intermediate plate 3; they being assembled upon suitable pegs 4, preferably

rigidly fixed to the base plate 1 and cooperating with suitable screws 5 for holding the plates in position; the intermediate plate 3 being spaced approximately centrally between the base and cover plates and so held by suitable spacers around the bolts as is common in locks of this general character.

The horizontally reciprocal bolt 6 of the lock is mounted upon the face of the intermediate plate 3 next to the covering plate and is bifurcated at its rearmost end, as at 7, and carries a guiding lug 8 adjacent the opposite end which extends through a suitable elongated slot 9 in the intermediate plate; there being a fixed bolt or rivet in the intermediate plate extending through the bifurcated slot 7 for guiding the innermost end of the bolt. The bolt 6 is cut out 75 from its lower edge upwardly forming an angularly shaped recess 10 therein and which is slightly nearer the inner end of the bolt than the outer end. Directly beneath this cut-away portion is the key hole 11, it 80 being preferably positioned centrally of the lock.

Upon the opposite side of the intermediate plate to that upon which the bolt 6 is mounted, is pivotally carried the catch 12, 85 its pivotal connection being upon the bolt 13 which extends through the plate and guides the bifurcated end of the bolt. This catch is so positioned as to normally operate by gravity in locking the bolt, but is also 90 provided with a small leaf spring 14 attached as at 15 with its opposite end fitting into a suitable slot in the lower edge of the catch 12, adjacent its pivotal point and which spring is so tensioned as to assist in 95 keeping the free end of the catch in its depressed position.

The free end of the catch 12 is bifurcated by a rectangular slot, indicated at 16, the upper edge of which is stepped, as at 17, so 100 that when the bolt 6 is in its extended locked position, the lug 8, carried thereby and protruding through the slot 9, will be engaged in said stepped portion 17 of the catch and thus held against backward movement by 105 the catch having dropped into such position behind the lug. Then it becomes impossible to retract the bolt until the free end of the catch 12 is raised, and the mechanism for performing this operation will be described 110 later when the peculiar construction of the key is described.

However, when the catch is raised to a horizontal position, as shown in Figure 4 of the drawing, the bolt may be freely slid backward, as the lug 8 will pass into the bifurcated slot 16 and assume the position shown in Figure 4. The free end of the bolt 6 protrudes through a suitable opening in the edge of the covering plate 2 of the lock, not particularly shown and may engage any form of escutcheon as is common in such locks, the same not being shown.

There is a key hole 11 through the intermediate plate 3 and about the upper portion of which is a circular bead 18, the ends of which terminate in the edges of the lower portion of the key hole. The lower portion of the key hole 11 has no offset cutaway portion as has the key hole 19 through the cover plate 2, as this latter key hole may be made of any shape to accommodate the actuating arm of any desired form of key made to cooperate within the cutaway recess 10 of the bolt 6.

Now the key for this particular type of lock comprises a hollow cylindrical shank 20, in which is reciprocally carried the spindle or shaft 21, terminating in the handle end of the key in a knurled thumb knob 22, this knob occurring inside of the pivotal handle ring 23 of the shank 20. Upon the opposite end of the spindle 21 is fixed a depending actuating L-shaped arm 24 which may be extended beyond the actuating arm 25 which is rigidly fixed to the shank 20 of the key proper or may be withdrawn into said actuating arm, there being a recessed portion and slot 26 within said arm 25 for such purpose and, when the arm 24 is drawn backwardly into the arm 25, the faces of the arms 24 and 25, comprising the end of the key, will be flush, this interlocking arrangement of the arms being for the purpose of normally keeping the same in alignment and from being accidentally damaged.

Assuming that the bolt 6 of the lock is in its retracted position and it is desired to extend the same to locked position, all that is necessary is to insert the key, when in its closed position, just previously described, into the key hole 19 and rotate the same until the actuating arm 25 has engaged the notch 10 and thrust the bolt 6 forwardly when the lock is locked. As soon as the bolt 6 is thrust forwardly the catch 12 will have dropped down behind the lug 8 and will securely hold the bolt against being returned to its retracted position without said catch being first disengaged from the lug. To accomplish this, when such is desired, the key is again inserted within the key hole 19, but not rotated until the spindle 21 is thrust forwardly by the convenient finger manipulation of the knob 22, when the arm 24 will have passed through the key

hole 11, and the arm 24 rotated until brought upwardly against the under edge of the catch 12, where a hole 27, through the plate 3, is formed for the reception of the inwardly turned end 28 of the arm 24, and said member 28 is pulled into the hole 27 by a withdrawing effort applied to the knob 22. This action will temporarily hold the arm 24 and spindle in position while the key proper may be rotated, the actuating arm 25 engaging the bolt 6 and returning it to its original position within the lock, when reverse manipulation of the spindle 21 will result in its being withdrawn from engagement through the key hole 11 and permit of the key being withdrawn from the lock.

When the arm 24 is rotated about in position within the lock it will overlap the bead 18 and thus be kept spaced from the face of the plate 3 to insure positive engagement with the catch 12; and, it is obvious that if a central pin, about which to rotate the key, is desired, as is common in such locks, the same may be employed without constituting any patentable difference in the construction of the lock.

Having thus described our invention, what we claim and desire to secure by Letters Patent, is:

1. The combination with a lock of the character described having a reciprocal bolt therein and an automatically operated catch cooperatively engageable with the bolt, of a key therefor composed of an inner and outer telescopic portion both of said portions having bolt engaging arms thereupon, means for operating the inner portion both longitudinally and rotatably independently of the outer portion, and means whereby the bolt engaging arm on the inner member is normally housed within the bolt engaging arm of the outer portion.

2. The combination with a lock of the character described having a reciprocal bolt therein and an automatically operated catch cooperatively engageable with the bolt, of a key therefor composed of an inner and outer telescopic portion and means for operating the inner portion both longitudinally and rotatably independently of the outer portion, the outer portion having a slotted bolt engaging arm thereupon and the inner portion having a bolt engaging arm thereupon normally housed within the slot in the arm of the outer portion.

In testimony whereof we hereunto affix our signatures in the presence of two witnesses.

JOSEPH W. KOVACH.
TONI MARKOVICH.
